UNITED STATES PATENT OFFICE.

HERBERT J. C. WELLS, OF NEW YORK, N. Y.

THERMOSTATIC DEVICE.

1,392,031.

Specification of Letters Patent. Patented Sept. 27, 1921.

Application filed September 20, 1919. Serial No. 325,091.

To all whom it may concern:

Be it known that I, HERBERT J. C. WELLS, a subject of the King of Great Britain, residing at New York, in the county and State 5 of New York, have invented certain new and useful Improvements in Thermostatic Devices, of which the following is a full, clear, and exact description.

The invention upon which is based the 10 present application for Letters Patent, is embodied in a novel form or construction of a device belonging to that class of temperature regulators in which an expansible fluid is employed as the operating medium.

15 Heretofore all thermostatic regulators of this general class, within the temperature range for which the type is more particularly adapted, that is to say from 20° to 350° F., have been so designed that the thermostatic element proper, was inserted in the medium, the temperature of which it was proposed to control. In contradistinction to this, by my present invention, the medium to be controlled, passes through or is surrounded by the expansible controlling medium, by which means a more sensitive control is provided for, and a better contact for heat absorption insured.

In carrying out my invention, I use two 30 substantially parallel concentrically arranged tubes, joined at their ends, to form between them an intermediate space in which is contained an expansible fluid. This constitutes a thermostat proper, and the arrangement is preferably such that the medium, the temperature of which is to be controlled, enters, passes or flows through the inner tube, so that the expansible fluid between the walls of the two tubes absorbs heat 35 from the said controlled medium, or conversely gives up its heat to such medium, thereby increasing or diminishing the pressure within the inclosed space in which such fluid is contained. To realize the advantages

40 of this invention to the full, I employ in connection and in direct communication with the inclosed thermostatic chamber, a receptacle or chamber containing a diaphragm with which is operatively connected 45 a controlling valve, lever or other similar device.

The details of the apparatus thus generally described are of little moment provided they be such as to secure the relations 50 and the mode of operation above set forth.

In the accompanying drawing I have illus-

trated the improvement in its most practicable and preferred form, such drawing being a sectional view of the apparatus on a somewhat enlarged scale.

60 The device comprises an outer tube 1, the ends of which are in any proper manner connected up with a pipe or tube 2 through which flows the fluid or medium to be controlled. Within the tube 1 is a second tube 65 3 of high heat conductivity and preferably composed of corrugated sheet metal, the ends of which are properly secured to the ends of pipe 2 so as to form a closed annular space between the said inner and outer 70 tubes. This space is filled with any suitable expansible fluid 4.

Communicating with this annular space is a chamber of any proper character 5, preferably a tube with its lower or free end 75 closed and having united thereto a sheet metal cylindrical and corrugated tube 6 closed at its upper or free end and constituting an expansible diaphragm. To the end or head 7 of this tube is connected a rod 8 80 which passes through the closed end of the tube 5 and is connected with a valve 9 in a pipe 10, or to any other regulating or controlling device as the case may be.

The temperature of the expansible fluid 4, 85 and that of a medium flowing through the pipe 2, tend with great sensitiveness to approximate and the interchange of heat is very rapid, so that, for example, if the temperature of the medium in pipe 2 rises, the 90 expansible fluid quickly absorbs heat and expands. This expansion, communicated to the diaphragm chamber, exerts on the latter a pressure that contracts it, and thereby operates to close the valve 9 and so permit, 95 in this case, a diminished flow of the heating medium to a hot water heater, which permits the lowering of the temperature of the medium in pipe 2.

As a means of regulating the action of the 100 thermostat, I have shown a tube 11, the opposite ends of which are connected to the annular chamber containing the expansible fluid. This tube 11 contains a diaphragm 105 preferably of the same character as that above described, but the rod 12 connected with the head 13 is seated on a spiral spring 14, adjustable in position by means of which the opposition to the longitudinal movement of the rod under the pressure created in the 110 tube by expansion of the fluid 4 may be regulated and controlled. By means of this

device the aggregate capacity of the chamber containing the expansible fluid is regulated as need may be.

This device has many uses. For example, 5 it may be employed to control the supply of cooling water to the jackets of gas or oil engines, or, in general, to regulate the supply of either a cooling or a heating medium to any other form or kind of apparatus that 10 may require it.

What I claim as my invention is:

1. A temperature controller having a plurality of chambers, one of which surrounds 15 and is separated from the other by a wall of high heat conductivity in combination with means for conveying to and from the inner chamber fluid whose temperature is to be controlled, a regulating device operatively connected to the outer chamber to be controlled by the change in volume of liquid 20 in said outer chamber, and adjustable means for varying the volume of said outer chamber to select the temperature at which said regulating device responds.

25 2. The combination in a temperature con-

troller of two concentric tubes, the inner tube being corrugated to increase the exposed surface, said tubes forming a closed annular space which is filled with an expansible medium, of means operated by the expansion 30 and contraction of said medium for actuating a regulating device, and means for passing through the inner corrugated tube the medium of which the temperature is to be controlled.

3. A thermostatic temperature controller comprising in combination two concentrically arranged tubes, the inner tube being corrugated and of a high heat conductive material, said tubes forming an intermediate 40 chamber, the inner tube forming a passage for a medium of which the temperature is to be controlled, and the intermediate chamber containing the expansible fluid, the variations in pressure of which are utilized for 45 purposes of regulation.

In testimony whereof I hereunto affix my signature.

H. J. C. WELLS.
